UNITED STATES PATENT OFFICE

NELLIE STONE, OF WILLAMINA, OREGON

MARCELLING IRON

Application filed August 28, 1928. Serial No. 302,617.

My invention relates to improvements in marcelling irons, and it consists in the combinations, constructions and arrangements hereinafter described and claimed.

An object of my invention is to provide a marcelling iron that may be worked in much the same manner as hair clippers. The handles of the iron when actuated, move forked members laterally with respect to other forked members. Hair has previously been received between the prongs of the members, and this movement of the members will form the hair into waves.

The forked members may be electrically heated, or they may be heated by placing them over a flame.

I also provide novel means for preventing the bottom of the iron from scorching the scalp.

Other objects and advantages will appear in the following specification, and the novel features of the device will be particularly pointed out in the appended claims.

My invention is illustrated in the accompanying drawings forming a part of this application, in which

Figure 1 is a longitudinal section through the iron;

Figure 2 is a section along the line 2—2 of Figure 1;

Figure 3 is a section along the line 3—3 of Figure 2;

Figure 4 is a section along the line 4—4 of Figure 1;

Figure 5 is a view similar to Figure 4 but showing the forks in a moved position;

Figures 6, 7, 8 and 9 are plan views of the four forks;

Figure 10 is a plan view of a part of the device; and

Figure 11 is a section along the line 11—11 of Figure 10.

In carrying out my invention, I provide a number of forks indicated by the reference numerals 1, 2, 3 and 4 (see Figure 1). Each fork has four prongs as shown in Figures 6 to 9 inclusive. The forks are placed one above the other and the prongs form hair-receiving slots, or recesses, as shown in Figure 4.

The forks are movable so as to dispose the prongs in the position shown in Figure 5. This movement causes the hair to be waved.

The forks 1 to 4 inclusive are shaped so as to fit one above the other, and the forks 2 and 4 are designed to move laterally with respect to the forks 1 and 3. I will first show how the forks contact with each other and then how the forks 2 and 4 are moved with respect to the others.

Reference to Figure 9 shows a plan view of the fork 1. The outside prongs of this fork are curved as at 5 for a purpose hereinafter described. A ridge 6 is provided immediately in back of the prongs and upon the upper surface of the base 7. The base has two openings 8 and 9 therein for receiving screws 10 (see Figure 1). A second ridge 11 co-operates with the ridge 6. At the extreme end of the base 7 I provide a countersunk opening 12 for receiving a bolt 13 (see Figure 1).

The fork 2, shown in Figure 8, has slots 14 and 15 for receiving the screws 10 because this fork moves with respect to the fork 1. The base 16 of the fork 2 has a projection or rider 17 for contacting with the rider 11 (see Figure 1) and a rider 18 on its upper surface.

The fork 3 has openings 19 and 20 for receiving the screws 10 and a large rectangularly-shaped opening 21 for receiving a part of the operating mechanism to be hereinafter described. An opening 22 receives the bolt 13.

The bolt and the screws 10 hold the fork 3 stationary. The base 23 of the fork 3 has a rider 24 that bears upon the base 16, and a rider 25 that also bears upon this base. The fork has a rider 26 upon its upper surface.

In Figure 6 I show the fork 4. This fork has slots 27 and 28 similar to the slots 14 and 15, and a recess 29 similar to a slot 30 in the base 16. Riders 31 and 32 project downwardly from the base 33 and rest upon the base 23.

All of these forks are mounted one upon the other as shown in Figure 1. They are then connected to the operating mechanism which will now be described.

Reference to Figures 1 to 3 inclusive shows

this mechanism as being mounted upon a frame 34. The frame has an integral handle 35 (see Figure 3) and threaded recesses 36 and 37 for receiving the screws 10. Guide members, or riders 38, project downwardly from the under surface of the frame 34 and bear upon the top of the base 33 (see Figure 1).

A second handle 39 is pivoted on the bolt 13 and a spring 40 tends to swing this handle into a position where it will engage with a stop member 41 (see Figure 3). The handle carries a depending member 42 (see Figure 1). This member enters the recesses 29 and 30 of the forks 2 and 4 and an opening 21 in the fork 3. The recesses 29 and 30 are just large enough to receive the member 42; therefore, a movement of the handle with its consequent movement of the member 42 will cause the forks 2 and 4 to move with respect to the other forks.

This movement is at right angles to the longitudinal axes of the forks due to the screws 10 riding in the slots 14, 15, 27 and 28. The opening 21 is made large enough to permit the member 42 to move freely therein.

From the foregoing description of the various parts of the device, the operation thereof may be readily understood.

The prongs of the forks are normally arranged in the position shown in Figure 4. A movement of the handle 39 will move the prongs into the position shown in Figure 5 as already stated. In Figure 1 I have shown electrical heating elements 43, and these are placed in the prongs.

In Figures 10 and 11 I show a U-shaped base 44 having metal, semi-circular elongated members 45 secured to its legs. The base 44 is preferably made of wood, or some other non-conducting material. The members 45 are slid into the grooves 5 in the fork 1 (see Figure 4). The member rests upon the scalp and spaces the forks away from the head. This prevents the burning of the scalp.

The handles 35 and 39 are provided with wooden gripping members 35' and 39' respectively.

I claim:

1. A marcelling iron comprising a plurality of forks disposed one above the other and means for moving certain of said forks laterally with respect to the others, the other forks remaining stationary.

2. A marcelling iron comprising a frame, a plurality of forks mounted thereon, certain of said forks being movable with respect to said frame while the others are rigidly secured thereto, a handle pivoted to said frame and being operatively connected to said movable forks, and guide means for causing said movable forks to move laterally with respect to the other forks and to said frame.

3. A marcelling iron comprising a frame, a plurality of forks mounted thereon, certain

of said forks being movable with respect to said frame while the others are rigidly secured thereto, a handle pivoted to said frame and being operatively connected to said movable forks, guide means for causing said movable forks to move laterally with respect to the other forks and to said frame, and a member removably secured to the lowermost fork for spacing it away from a person's head, the outermost prongs of the lowermost fork having grooves, said member having ribbed portions receivable in the grooves.

4. A marcelling iron comprising a frame, four sets of forks disposed one above the other, means for securing said forks to said frame, the alternate forks being movably secured to the frame, means for actuating said movable forks for causing them to move laterally with respect to the other forks and to the frame, said forks being provided with shoulders that extend throughout the width of the forks, said shoulders spacing the forks apart and being narrow in width so as to reduce the amount of friction between the moving parts.

5. A marcelling iron comprising a frame, a plurality of forks disposed one above the other, pins for securing said forks to said frame, certain of said forks having slots for permitting lateral movement of these forks with respect to the others and to the frame, a handle operatively connected to said movable forks for causing the prongs of these forks to move laterally with respect to the prongs of the other forks, and spring means for returning the movable forks to normal position whereby the prongs of all of the forks will be aligned one above the other.
